PLATE STEEL HEAD COVER

Robert E. Brunswick Sharp, Philadelphia, Pa., assignor to Baldwin-Southwark Corporation, a corporation of Delaware

Application March 18, 1932, Serial No. 599,669

10 Claims. (Cl. 253—117)

This invention relates generally to hydraulic machines and more particularly to an improved hydraulic turbine plate steel head cover having the component plate steel elements thereof so 5 constructed and arranged that they may be easily rolled or otherwise formed in a manner which is economical and will provide the necessary rigidity and stability of construction such as is necessary in hydraulic apparatus.

10 One object of the invention is to provide an improved plate steel head cover and particularly one with two principal elements of dish formation so that, for example, they may be readily spun, rolled or easily pressed by a simple press 15 and die. A further object is to form the parts so as to present a construction which permits the members to be effectively welded without subjecting the weld to abnormal strains. If under certain conditions it is desired to have the members 20 detachably connected together, the component elements may be suitably bolted or riveted together but in any event it will be seen from the disclosure herein that a relatively simple and economical construction has been devised.

25 Other objects and advantages will be more apparent to those skilled in the art from the following description of the accompanying drawings in which:

Fig. 1 is a vertical section through an open flume propeller type setting.

30 Fig. 2 is a perspective of a portion of the head cover to show the arrangement of ribs.

Fig. 3 is a vertical section showing the manner in which my improved head cover is employed 35 in a Francis turbine.

While the invention is particularly adapted for an open flume turbine setting, it will of course be understood that the structure and principles of construction are equally applicable to Francis 40 type turbines, as shown in Fig. 3, or to various types of propeller turbines or pumps as shown in Fig. 1. The particular specific embodiment of the invention as shown in Fig. 1 comprises an inlet passage 1 in which a series of usual adjustable guide vanes 2 are disposed. These guide vanes are adjustably supported by stay bolts 3 which support the head cover, generally indicated at 4, in spaced relation to the lower distributor generally indicated at 5. The stay bolts 45 have enlarged portions 6 at each end thereof to provide shoulders engaging the head cover and the lower distributor ring 5 in which holes are provided for receiving the reduced ends 8 of the stay bolts. The distributor plate 5 can be either 50 cast or formed of heavy plate metal circularly 55

machined. An annular guide ring 10 also formed of plate steel is suitably welded to distributor plate 5 at the two points 11 while radially extending vertical plate metal ribs 12 are suitably circumferentially spaced to support ring 5. A horizontal circular flange 13 may also be added if desired and all of these elements are preferably suitably welded together, for instance as at 14. The draft tube may have a relatively thin circular plate metal wall 15 welded as at 16 to 10 ring 10.

The inner corner 7 of distributor plate 5 is preferably machined to provide a curved surface to suitably guide the water while the outer periphery of plate 5 is provided with a recess 17 in which is disposed a plate metal or cast shifting or operating ring 18, the outer periphery of which is suitably downwardly curved to provide a flange 19 for purposes of strength and rigidity in addition to providing a smooth curved surface to the 20 beginning of the turbine entrance passage. Suitable bearing metal may be disposed in recess 17 for insuring proper wearing and ease of operation of the shifting ring.

The shifting ring is suitably connected to each 25 guide vane by a suitable pin and link generally indicated at 20 while the gate operating servomotor may be connected to a bearing 21 which consists of a short bearing extending through an opening in and welded to a plate metal extension 30 22 projecting outwardly from and welded to the flange 19.

The lower distributor plate construction as above described is suitably anchored or embedded in preferably a concrete foundation 23 while anchor bolts 24 are connected to suitable angle members 25 which are secured, as by welding, to rim 35 10 and plate 7.

Head cover 4 comprises a circular piece of plate metal having a relatively flat portion 25, an inner 40 downwardly curved portion 26 and an outer upwardly curved portion 27. It is seen that the turning of the inner and outer portions toward axial directions is conducive to a relatively simple forming operation either by rolling such as spinning 45 or by dies of simple formation and due to the flange-like portions 26 and 27 being at the inner and outer ends of the intermediate portion 25, a very desirable rigid construction is created. The portion 25 forms not only one wall for inlet 50 passage 1 and a transition space 28 but also forms the upper distributor plate adjacent the upper ends of guide vanes 2. There is further provided a preferably relatively thinner plate metal member 30 terminating adjacent a hub 31 of a high 55

specific speed propeller type runner 32 whose blades are relatively few in number, for example, preferably six or less and are relatively flat in the direction of fluid flow thereover and are inclined 5 at a relatively small angle with respect to a plane normal to the runner axis.

To form the top portion of the head cover there is provided an upper plate 33 formed in somewhat the general manner of the lower plate 25, 10 it being noted that plate 33 is of dome shaped formation preferably with its periphery turned downwardly to provide a flange like portion 34 adapted to rest upon and be welded to preferably the upper edge of flange 27.

15 The dome shape of plate 33 adds considerable strength to the general head cover construction, and this strength additionally effects a rigid unitary structure throughout the low-head cover especially when supplemented by the provision of 20 a series of radial webs 35 terminating at their inner ends at 36 and at their outer ends at 37 adjacent a series of pipes 38 which extend through openings 39 formed in plate 33. These pipes are disposed in axial alignment with each of the stay 25 bolts 3 and are welded to plates 25 and 33. Instead of using material such as a piece of pipe the passageway 40 leading to stay bolts 3 may be formed of any other suitable material although pipe sections provide a very economical and yet 30 thoroughly solid and desirable construction.

In addition to the series of circumferentially spaced vertical flanges 35 there is also provided a second series of alternate flanges 41 whose inner ends terminate at 42 while their outer ends 35 have about the same radial extent as ribs 35. The ribs 41 project downwardly as indicated at 43 to have contact with conical plate 30 and an annular plate 44, all of which are suitably welded together. The inner edges of lower projections 43 terminate as at 45 to provide an offset shoulder 46 upon which may rest a suitable bearing plate generally indicated at 47. A bearing 48 is thereby supported at its upper end while its lower end is suitably supported by a ring 49 welded to an 45 annular plate 44. The runner shaft 50 extends upwardly through both the bearing and a space 51 which is provided with a suitable removable plate metal cover 52 of flat annular formation.

The outer ends of lateral stud bolts or rods 53 50 are suitably fastened to the usual surrounding structure of concrete or other material while their inner ends may be secured to plate metal or cast angle anchorages 54 suitably welded to the upper dished plate 33. If the turbine is of the type having an inlet casing, such for example as a volute, 55 partially shown at 60, Fig. 3, so as to make it desirable to provide a shifting ring 61 on top of the head cover, it is readily seen that the shifting ring guides 62 may be directly welded to the top of 60 dished plate 33 and the guide vane operating rods should extend upwardly through passages 40 for connection to the shifting ring through links 63. Fig. 3 also illustrates the application of my improved head cover to a Francis turbine as hereinbefore mentioned wherein a Francis runner 64 has its hub 65 forming a curved continuation of a head cover plate 25' which extends radially from the shaft 50 and bearing 47'. The remaining head cover structure has all of the structural and functional characteristics of the Fig. 1 arrangement.

70 From the foregoing disclosure it is seen that my improved construction employs component plate metal elements so formed that they may be readily rolled or otherwise easily shaped and assembled 75 in such a manner that, if desired, the parts may

be effectively welded together, while the pipe sections forming passages to guide vane stay bolts provide a very simple and yet effective construction. If desired the lower edge of plate 25 may be suitably machined as at 56 adjacent the ends 5 of guide vanes 2 to reduce leakage to a minimum around the guide vanes. It will also be noted that for the most part the ribs and component plate metal parts have substantially straight line contact at their line of juncture thus greatly facilitating the assembly and manufacture of the various plate metal elements.

10 It will of course be understood by those skilled in the art that various changes and rearrangements of parts may be made without departing 15 from the spirit of the invention as set forth in the appended claims.

I claim:

1. A plate metal head cover for a hydraulic machine comprising a circular plate metal member having inner and outer portions extending toward opposite axial directions, and a conical plate metal member formed separately from but secured to the inner axial portion of said circular plate to form a continuation thereof, both of 20 said members being formed along substantially straight line elements extending over the major portion of the length of said members.

2. A plate metal head cover for a hydraulic machine comprising a plate having an inner circular portion turned toward an axial direction, and a conical plate metal member formed separately from but rigidly secured to said axial portion to form a continuation thereof, both of 30 said plates having the major portion of their length formed with substantially straight line generatrices.

3. A plate metal head cover for a hydraulic turbine or pump comprising a single plate metal member forming both an upper distributor plate 40 and a wall of a transition space disposed inwardly of the distributor portion, said plate being circular and having its outer portion turned toward an axial direction to provide a peripheral flange, and a dome shaped plate metal member rigidly 45 secured to said peripheral flange.

4. A plate metal head cover for a hydraulic turbine or pump comprising a single plate metal member forming both an upper distributor plate and a wall of a transition space disposed inwardly of the distributor portion, said plate being circular and having its outer portion turned toward an axial direction to provide a peripheral flange, and a dome shaped plate metal member having 50 its outer portion turned toward an axial direction 55 to provide a flange which is rigidly secured to said peripheral flange to provide a unitary head cover structure.

5. A plate metal head cover for a hydraulic machine comprising opposed circular plates one of which is permanently supported by and rigidly secured to the other adjacent their peripheries, the lower one of said circular plates forming a 60 passage wall for conducting water through the hydraulic machine and the upper one of said circular plates being of dome shape, and a series of 65 circumferentially disposed radially extending vertical ribs positioned between said circular plate metal members and rigidly secured thereto.

6. A plate metal head cover for a hydraulic machine comprising opposed circular plates one of which is supported by and rigidly secured to the other adjacent their peripheries, the lower one of said circular plates forming a passage wall 70 for conducting water through the hydraulic ma- 75

chine and the upper one of said circular plates being of dome shape, a circular plate metal member rigidly secured to and projecting axially from one of said opposed circular plates, and vertical 5 ribs projecting inwardly therefrom and rigidly secured thereto to provide a support for a shaft bearing.

7. A plate metal head cover for a hydraulic machine comprising opposed circular plate metal members one of which has a peripheral flange extending toward an axial direction and rigidly supported by the other of said members, and pipe like members secured to said opposed members to provide passageways therethrough, the 10 lower one of said circular plates forming a passage wall for conducting water through the hydraulic machine and the upper one of said circular plates being of dome shape.

8. A combined plate metal head cover and upper distributor ring for a hydraulic machine comprising a dome shaped plate metal member and an opposed circular plate metal member rigidly supported with said dome shaped member in spaced relation thereto, a lower distributor 15 ring, guide vane shafts supported by and between

said upper and lower distributor rings, said plate members having openings, and means connected to said plate members adjacent said openings to provide a passageway extending through said plate members to said vane supporting means. 5

9. A hydraulic turbine setting comprising a lower plate metal distributing ring, a plate metal annular ring projecting downwardly from and welded to the inner edge of said distributor ring, and ribs disposed between said distributor and annular rings for holding the same in rigid relation, a plate metal operating ring having a flat annular portion and a flanged peripheral portion, and said distributor ring having provision for journaling thereon said annular portion of the 10 15 operating ring.

10. A plate metal setting for a hydraulic machine comprising a lower distributor plate having an annular recess for journaling a plate metal shifting ring, said plate metal shifting ring having a flat annular portion journalled in said annular recess and a peripheral flange relatively gradually turned to provide a smooth inlet surface. 20
